W. FREEGARD

FLEXIBLE SHINGLE

Filed Oct. 30, 1924

FIG. I.

FIG. II.

FIG. III.

FIG. IV.

WITNESSES:

Foley Paul
ATTORNEYS.

UNITED STATES PATENT OFFICE.

WILLIAM FREEGARD, OF ST. LOUIS, MISSOURI, ASSIGNOR TO THE BARBER ASPHALT COMPANY, OF PHILADELPHIA, PENNSYLVANIA, A CORPORATION OF WEST VIRGINIA.

FLEXIBLE SHINGLE.

Application filed October 30, 1924. Serial No. 746,751.

This invention relates to shingles and it has more particular reference to the flexible variety made from asphaltum impregnated material coated on one or both sides with a mineralized surfacing. Shingles of the type referred to are usually made in individual form, or as strips having one longitudinal edge configured to simulate a series of shingle ends, so that when laid in successive courses and more or less interengaged they have the appearance of diagonally laid shingles. Such shingles are either arranged end to end in successively superposed overlapping rows, or are diagonally laid to afford what is generally known as a "point-down" appearance; and my invention has reference more specifically—though not essentially—to shingles adapted to the latter manner of disposition.

The primary object of this invention is to provide an improved form or pattern of shingle, which when laid, for covering a roof or other surface, interlocks to constitute a continuous exposed surface adapted to effectively withstand all climatic ravages.

Another object is to provide a unit shingle which when laid in multiple presents two full thicknesses of material as the weathering surface at all points thereover.

A further object is associated with the shape of my novel shingle units whereby—when laid—they better emphasize the "shadow line" so essential to relieve the monotony of surfaces covered with composition shingles.

With the foregoing and other objects in view, as will be later on referred to, this invention affords a new form and configuration of shingle strip units cut from prepared material without waste in such a manner that said units may be laid in diversified fashions without leaky joints.

Fig. I is a plan view of a length of flexible shingle material showing the manner in which my novel form of shingle units are cut therefrom without appreciable waste.

Fig. II is a plan view of an individual shingle unit with one corner retroverted ready for application to a roof or other surface.

Fig. III is a fragmentary plan view of a

surface covered with my novel form of shingles diagonally laid; and,

Fig. IV is a sectional view taken approximately as indicated by the arrowed lines IV—IV in the preceding figure.

Before proceeding with a detailed description of the characteristic configuration of my novel shingle units it is desirable to point out that they are conveniently formed from impregnated roofing felt usually furnished in rolls. In carrying out my invention I make use of a standard width of asphaltum impregnated material 5 having parallel longitudinal edges 6, and I bisect said material substantially along its center by an irregular dividing line 7. This line 7 it will be best seen from Fig. I, separates the length of material 5 into two corresponding parts each of which is transversely severed in relatively staggered relation by cross-cuts 8 to form shingle units 9. Thus it will be readily understood that the dividing line 7 between the two rows of shingle units 9 becomes the profile of each row and produces strips which are an exact replica of each other, while the cross-cuts 8 form the separate units 9; the back of one such unit forming the front of the next adjoining one, without scrap or waste. As is well known in the art the foregoing operations may be effected as one by passing the material 5 through appropriately fashioned cutting rolls, hence further description is deemed unnecessary.

Specifically explaining an individual shingle unit 9, as shown in Fig. II, it will be seen that the same is bounded by an upper straight edge 10, front and back edges 11, 12 respectively, which are the counterpart of each other, and the lower edge 13 embodying a portion of the irregular dividing line 7 aforesaid. At this juncture it is to be particularly observed that while I have designated the dividing line 7 as irregular—speaking in a general sense—it is, defacto, formed of alternating lengths of corresponding outline reversely aligned. In other words, and as best understood from Fig. I, the profile or dividing edge 7 of a unit *a* for example affords—when severed—the opposed part-profile or dividing edge of

two consecutive, but relatively staggered, units *b*, *c* respectively.

Again it is particularly noteworthy that the aforesaid dividing line 7 is of an outline 5 to provide each successively severed shingle unit 9 with a diagonally related tab 14 of polygonal configuration, the same being adapted for retroversion along the line or crease 15 to constitute an interlocking flap 10 having laterally projecting tips 16 for a purpose hereafter fully explained. This underfolded or retroverted tab 14 becomes a key for interlocking each unit 9 with the next layer when assembled as a roof or other surface covering, thereby entirely dispensing with any connecting metallic staple or other means common in the art to prevent buckling while accommodating free expansion and contraction of the sub-structure.

20 Shingle units 9 formed and configured, as above set forth, are preferably—though not essentially—diagonally laid when applied to a roof or other surface, as illustrated in Fig. III, thereby presenting a “point-down” appearance and finish. The manner of laying the novel shingle units 9 is simplicity itself; the same being automatically spaced as each unit is laid, by first inserting the retroverted tab 14 in the notched-out-part 17 of the underlying unit 9 and below the stepped portion 18 in the side edge 12 of the adjacent unit, and then aligning the shingle unit parallel to the top or straight edge 10 of said underlying unit. This feature entirely eliminates 30 all necessity for previously lining out the surface to be covered before applying the shingles 9 as now commonly obtains in the art. At this point it is also to be remarked that the notched-out-part 17 above referred to 35 is located intermediate the ends of the lower edge 13 of each unit 9, and is the complementary recess formed when cutting each tab 14. Again it will be fully appreciated from an inspection of Fig. III, that the inclined edge 19 of each shingle unit 9 materially aids the laying operation by defining an indicator point 20 to which the top edges 10 can be promptly registered as will be clearly understood on an examination of the assembly view. Again it is observable that the connection accomplished by the retroverted tab 14 when passed through the notched-out-part 17 and slid under the preceding subjacent shingle edge is of an interlocking character, and that it functions as a key which cannot be pulled upward or outwards. As shown, the medially overlapping and interlocked units lie in rows in one direction, while in another direction the corresponding 50 units of said rows lie in courses; the units of each course successively overlapping and interlocking at their margins, as at 19 in Fig. III.

60 It will, of course, be well understood that when each successive unit 9 is interlocked in

the manner set forth, said unit is secured with one or more nails 21—Fig. III—in the well known way, said nails however being completely covered by the succeeding layer of shingle units.

From the foregoing description it is thought that the numerous advantages inhering to my novel form of shingle units 9 will be readily apparent, but among others attention is directed to the interlocking connection effected by the tabs 14 which renders the surface covering continuous, while allowing sufficient expansion and contraction in the same plane as the roof or wall to prevent warping. After such strains are taken up, 80 the tabs 14 will gradually seal to the next lower units. Again, while the description and drawings relate to a continuous two-ply assemblage of half-way overlapping courses of the shingle units 9, the general design 85 may be equally well adapted to a single-ply covering without departing from the characteristics of my invention. Furthermore, when my improved shingle units 9 are in place and diagonally laid the edges exposed 90 are so directed and held down by the tabs 14 that they cannot move up and down in high winds or work loose; while the finished appearance is of an unique and artistic character with the “shadow lines” very pronounced 95 and distinctive.

While I have described a preferred embodiment of the invention, it is to be clearly understood that I do not limit myself to the precise details set forth, but intend to include 100 herewith all other reasonable adaptations and modifications that fairly lie within the scope of the appended claims.

Having thus described my invention, I claim:—

1. A flexible shingle unit having an upper straight edge, a lower irregularly-configured edge an intermediate portion whereof affords an irregular notched-out recess, and a similarly configured retrovertible tab integral with one of the lower corners thereof. 110

2. A flexible shingle unit having an upper straight edge, a lower irregularly-configured edge an intermediate portion whereof affords a polygonal-shaped recess, and a corresponding polygonal-shaped retrovertible tab integral with one of the lower corners thereof. 115

3. A flexible shingle unit having an upper straight edge, a lower irregularly-configured edge an intermediate portion whereof affords a recess, and a polygonal-shaped retrovertible tab integral with one of the lower corners thereof, the other lower corner affording an indicator point for aligning consecutively laid units. 120

4. A flexible shingle unit having an upper straight edge, a lower irregularly-configured edge an intermediate portion whereof affords a recess and a diagonally directed re- 130

trovertible tab integral with one of the lower corners thereof, the other lower corner affording an indicator point for aligning consecutively laid rows of units.

5. A flexible shingle unit having an upper straight edge, a lower irregularly-configured edge an intermediate portion whereof affords a polygonal-shaped recess, and a corresponding polygonal-shaped retrovertible tab integral with one of the lower corners thereof, said tab being adapted for interlocking engagement with the recess of one previously laid unit and the side edge of another one.

6. A flexible shingle unit having an upper straight edge, a lower irregularly-configured edge an intermediate portion whereof affords a polygonal-shaped recess, and a corresponding polygonal-shaped retrovertible tab diagonally directed outward from one of the lower corners thereof, said tab being adapted for interlocking engagement with the recess of one previously laid unit and the inwardly-stepped side edge portion of another one.

25. 7. A flexible shingle unit having an upper straight edge, opposed parallel irregularly-lined side edges, a lower irregularly-configured edge an intermediate portion whereof affords a locking recess, and a retrovertible tab integral with one of the lower corners.

35. 8. A flexible shingle unit having an upper straight edge, opposed parallel irregularly-lined side edges, a lower irregularly-configured edge an intermediate portion whereof affords a locking recess, and a retrovertible tab integral with one of the lower corners, said tab being adapted for engagement with the locking recess of a previously laid

40. unit and the side edge of a subjacent one.

45. 9. A flexible shingle unit having an upper straight edge, opposed parallel irregularly-lined side edges, a lower irregularly-configured edge an intermediate portion whereof affords a locking recess, and a polygonal-shaped retrovertible tab integral with one of the lower corners.

50. 10. A flexible shingle unit having an upper straight edge, opposed parallel irregularly-lined side edges, a lower irregularly-configured edge an intermediate portion whereof affords a locking recess, a polygonal-shaped retrovertible tab integral with one of the lower corners, the other lower corner constituting an indicator point for aligning consecutively laid units.

55. 11. A flexible shingle unit having an upper straight edge and a lower irregularly-configured edge provided with an intermediate polygonal notched-out recess, and a retrovertible polygonal tab at one of the lower corners thereof; that portion of the unit including the tab simulating a point down

shingle, and the other portion being adapted to underlie the successively laid unit, whereby a continuous two-ply surface covering is ensured.

65. 12. A flexible shingle unit having an upper straight edge, a lower irregularly-lined edge affording a diagonally directed polygonal-shaped tab at one corner of the shingle unit, and a complementary-configured recess intermediate the ends of said lower edge.

70. 13. A shingling for surface covering comprising successive rows of adjoining shingle units, each unit having a retrovertible tab at one of the lower angular corners and a complementary-configured recess medially of the lower edge thereof, the tab of each shingle unit when retroverted and laid underlying the recess in one previously laid unit and the edge of another one.

75. 14. A surface covering comprising rows of successively overlapping shingle units having polygonal recesses intermediate the lower corners thereof, each unit in a row having a retrovert polygonal-shaped tab at a lower corner to interengage and underlap the polygonal recess in the lower edge of a subjacent unit in the row.

80. 15. A surface covering comprising flexible units each having a retrovertible polygonal-shaped tab at a lower corner and a complementary configured recess medially of the irregularly-configured lower edge thereof, said units being arranged in courses so that the aforesaid tabs of units in one course interlock with the recesses of the subjacent course, thereby producing a uniform two-ply thickness throughout the surface covered.

85. 16. A surface covering of shingling material comprising successive courses of diagonally laid shingle units, each unit having a retrovertible polygonal-shaped tab at one of the lower corners and a complementary configured recess in the irregularly-configured lower edge, each unit in a course having the tab thereof retroverted and interlocked with a recess in the subjacent course in underlapping relation, and said units when laid producing a uniform two-ply thickness throughout the surface covered.

90. 17. A surface covering comprising rows of shingles medially overlapping, each with a polygonal-shaped retrovert corner portion medially underlapping and interengaging a complementarily configured notch in the shingle beneath, corresponding shingles in adjacent rows marginally overlapping and interlocking, the upper under the lower.

95. In testimony whereof, I have hereunto signed my name at Fort Pierce, Florida, this third day of October, 1924.

WILLIAM FREEGARD.
